UNITED STATES PATENT OFFICE.

ROY EVERHART, OF MARSHALL, TEXAS, ASSIGNOR TO HIGHWAY ADVERTISING CO.,
OF MARSHALL, TEXAS.

DESIGN FOR A SIGNBOARD.

Application filed July 14, 1926. Serial No. 18,361. Term of patent 14 years.

To all whom it may concern:

Be it known that I, ROY EVERHART, a citizen of the United States, residing at Marshall, in the county of Harrison and State of Texas, have invented a new, original, and ornamental Design for a Signboard, of which the following is a specification, reference being had to the accompanying drawing, forming part thereof.

Figure 1 is a front elevation of a signboard showing my new design.

Figure 2 is an edge elevation thereof. The central plane field constituting a part of the signboard is an outline map of a geographical division.

I claim:—

The ornamental design for a signboard, as shown and described.

ROY EVERHART.
